APPARATUS FOR COMPRESSING AND
COOLING AIR

Adalberto Garelli, Milan, Italy

Application July 13, 1937, Serial No. 153,449
In Italy July 18, 1936

4 Claims. (Cl. 62—135)

This invention relates to air compressors and more particularly to high pressure air compressors and to single stage air compressors and has for its object means to remove causes of explosions which are liable to occur in compressed air plants fed by such compressors on account of self-ignition of lubricating oil which accompanies the air compressed by said compressors.

10 In accordance with this invention means are provided to cool the compressed air to such an extent as necessary to condensate the oil used for the compressor lubrication and carried off by said compressed air, as well as to prevent the 15 high temperature of the air from causing the vaporisation of the oil which may have collected in the reservoir or on the walls thereof to such an extent as to carburize the air contained therein and to develop conditions able to cause explosions 20 due to self-ignition.

By the means of this invention the above stated danger is removed in a simple and safe manner and thus it is possible to reach with full safety the highest pressures obtainable by means of 25 single stage compressors, this condition being particularly useful in compressors and in starting engine-compressor sets used in aircrafts, where highest requirements as to simplicity, light weight and safety are to be satisfied.

30 An embodiment of the present invention is hereinafter described by way of example with reference to the annexed drawing, in which:

Figure 1 is an elevational view of an engine-compressor set with an air-cooling arrangement 35 according to this invention;

Fig. 2 is a transverse section on line 2—2 of Fig. 1; and

Fig. 3 is a rear view in part in section on line 3—3 of Fig. 2.

40 These figures illustrate an engine-compressor set with air cooling in which the coil tube intended for cooling the air compressed in the compressor cylinder, is directly embodied in said set in such a way as to be cooled by the same combined fly-wheel and cooling air propeller devoted to cool the engine-compressor set. In said figures 10 denotes an engine cylinder which is shown conventionally to illustrate an engine cylinder of any approved class whose piston and rod actuate 45 a crank shaft which in turn actuates the rod and piston of a compressor cylinder 11 having an outlet valve; 12 is the fuel tank supplying fuel for the operation of the engine cylinder 10 and 13 is the outlet of compressed air from air 50 compressor cylinder 11. A cooling coil tube 3

is connected to said outlet 13 and the tube 15 leading to a compressed air reservoir (not shown) is connected at 14 to the outlet of said coil tube; 16 is a combined fly-wheel air propeller driven by the engine crank shaft and operative to cool said engine-compressor set and also said coil by the air stream induced by its rim blades 16' which draw air centrally and discharge it radially to flow over the cylinders 10 and 11 and coil 3.

Of course the present invention is not restricted to the described embodiments and includes all arrangements within the spirit of appended claims.

What I claim as my invention and desire to secure by United States Letters Patent is:

1. Means for producing and cooling compressed air for storage under high pressure, comprising a unit having an engine cylinder and an air compressor oil-lubricated cylinder, said cylinders having their axes located substantially in the same plane, a fly-wheel in said unit and lying in a plane located at one side of said cylinders, air propelling blades on the rim of said fly-wheel, a conduit leading from said compressor cylinder and adapted to be connected with a compressed air reservoir, said conduit comprising a portion located near the path of said blades and in the air stream promoted thereby and constructed to provide for a direct, smooth, unimpeded gravity flow of oil condensing from said air toward the discharge end of said conduit, and a hood embracing said engine cylinder, compressor cylinder, air propelling bladed fly-wheel and conduit portion.

2. Means for producing and cooling compressed air for storage under high pressure, comprising a unit having an engine cylinder and an air compressor oil-lubricated cylinder, said cylinders having their axes located substantially in the same plane, a fly-wheel in said unit and lying in a plane located at one side of said cylinders, air propelling blades on the rim of said fly-wheel, a conduit leading from said compressor cylinder and adapted to be connected with a compressed air reservoir, said conduit comprising a radiator located near the path of said blades and in the air stream promoted thereby and constructed to provide for a direct, smooth, unimpeded gravity flow of oil condensing from said air toward the discharge end of said conduit, and a hood embracing said engine cylinder, compressor cylinder, air propelling bladed fly-wheel and radiator.

3. Means for producing and cooling compressed air for storage under high pressure, comprising a unit having an engine cylinder and an air compressor oil-lubricated cylinder, said cylinders having their axes located substantially in the same plane, a fly-wheel in said unit and lying in a plane located at one side of said cylinders, air propelling blades on the rim of said fly-wheel, a conduit leading from said compressor cylinder and adapted to be connected with a compressed air reservoir, said conduit comprising a coil tube located near the path of said blades and in the air stream promoted thereby and providing for a direct, smooth, unimpeded gravity flow of oil condensing from said air toward the discharge end of said conduit, and a hood embracing said engine cylinder, compressor cylinder, air propelling bladed fly-wheel and coil tube.

4. Means for producing and cooling compressed air for storage under high pressure, comprising a unit having an engine cylinder and an air compressor oil-lubricated cylinder, said cylinders having their axes located substantially in the same plane, a fly-wheel in said unit and lying in a plane located at one side of said cylinders, air propelling blades on the rim of said fly-wheel, a conduit leading from said compressor cylinder and adapted to be connected with a compressed air reservoir, said conduit comprising a coil tube with vertical axis having an inlet at its upper end and a discharge at its lower end and located near the path of said blades and in the air stream promoted thereby, and a hood embracing said engine cylinder, compressor cylinder, air propelling bladed fly-wheel and coil tube.

ADALBERTO GARELLI.
